UNITED STATES PATENT OFFICE.

RAYMOND C. DICK, OF MANNINGTON, WEST VIRGINIA.

DESIGN FOR A BADGE.

No. 37,660.

Specification for Design.

Patented Nov. 14, 1905.

Application filed August 29, 1905. Serial No. 276,311. Term of patent 7 years.

To all whom it may concern:

Be it known that I, RAYMOND C. DICK, a citizen of the United States, residing at Mannington, in the county of Marion and State of West Virginia, have invented a new, original, and ornamental Design for a Base-Ball Badge, of which the following is a specification, reference being had to the accompanying drawing, forming a part thereof.

The figure is a plan view of a badge, showing the new design.

I claim—

The ornamental design for a badge, as shown.

RAYMOND C. DICK. [L. S.]
